Primary Examiner—M. N. Pandozzi**Attorney, Agent, or Firm**—Richard B. O'Planick; Lisa B. Riedesel**[57]****CLAIM**

The ornamental design for a lid for storage container, as shown and described.

DESCRIPTION

FIG. 1 is a top right front perspective view of a lid for storage container showing my new design;

FIG. 2 is a top plan view thereof;

FIG. 3 is a front elevational view thereof, the rear elevational view being a mirror image; and,

FIG. 4 is a right side elevational view thereof; the left side elevational view being a mirror image.
